UNITED STATES PATENT OFFICE.

BENJAMIN J. KIME, OF SENECA FALLS, NEW YORK, ASSIGNOR OF ONE-FOURTH TO
RANSOM R. MICKS, OF SENECA FALLS, NEW YORK.

CENTRIFUGAL-PUMP.

1,353,915.

Specification of Letters Patent. Patented Sept. 28, 1920.

Application filed November 21, 1919. Serial No. 339,531.

To all whom it may concern:

Be it known that I, BENJAMIN J. KIME, of Seneca Falls, in the county of Seneca, in the State of New York, have invented new and useful Improvements in Centrifugal Pumps, of which the following, taken in connection with the accompanying drawings, is a full, clear, and exact description.

This invention relates to certain improvements in centrifugal pumps and refers more particularly to means for automatically regulating the volume of liquid delivered by the pump according to the head or degree of back pressure produced by the liquid.

15 The ordinary centrifugal pump is designed to discharge a certain volume of liquid against a given pressure or "head" under a predetermined speed of the impeller which requires a given motor power to maintain the desired capacity of delivery, but it is found that if the "head" of the same pump is materially reduced it greatly increases the volume of discharge which, in turn, overloads the impeller and requires 20 more power for its operation than under the normal "head" for which the pump and its motive power were designed, so that if the "head" is materially reduced the pump and its motive power will cease to properly 25 function.

30 The main object of my invention is to provide simple and efficient means to automatically maintain approximately the same volume of delivery for a given period of 35 time under varying "heads" or height of water column so that a pump designed for a certain head may be efficiently operated under reduced heads.

35 In pumps of this character the intake opening in the impeller case is usually coaxial with the rotary impeller while the outlet is tangential thereto so that the rotation of the impeller serves to draw the liquid through the intake into the central opening in the impeller and to expel it through 45 passages leading from the center to the periphery of the impeller into the outlet, and one of the specific objects of this invention is to provide an automatic piston valve between the intake of the pump case and discharge passages of the impeller whereby the 50 degree of open communication between the intake and impeller passages will be normally reduced to a comparatively small degree, but is caused to gradually increase as

the back pressure on the impeller is increased by an increase of "head" or height of water column.

In other words, I have sought to regulate the delivery of water or other liquid through the passages of the impeller by means of a coaxially slideable piston valve having a piston head communicating with the outlet through the impeller chamber and its inner end extended into the impeller 60 across the adjacent ends of the passages therein and provided with radial openings registering more or less with said passages under varying pressures as the valve is operated by liquid pressure in one direction 65 against the action of a suitable retracting spring hereinafter described.

70 Other objects and uses relating to specific parts of the pump will be brought out in the following description.

75 In the drawings:—

Figure 1 is a longitudinal vertical sectional view of a centrifugal pump embodying the features of my invention.

Fig. 2 is an enlarged transverse vertical 80 sectional view of the same pump taken on line 2—2, Fig. 1.

Fig. 3 is an enlarged longitudinal sectional view of the detached impeller and piston valve.

85 As illustrated, the centrifugal pump comprises a base —1— having lengthwise journaled bearings —2— and —3—, an impeller case —4— having a central inlet —5— coaxial with said bearings —2— and —3— 90 and also having a circumferentially extending outlet —6— terminating tangentially at —7—.

95 An impeller —8— is secured to a rotary shaft —9— which is journaled in the bearings —2— and —3—, said impeller being rotatable in the case —4— and provided with a central opening —10— and a series of passages —11—, said opening —10— being coaxial with the inlet —5— of the case 100 while the passages —11— lead from the central opening in the impeller to the outlet —6— of the case.

105 A tubular valve —12— is mounted coaxially of and within the opening —10— in the impeller to slide endwise or axially across the inner ends of the passages —11— and is provided with an annular shoulder —13— co-operating with a portion —14— of the impeller for limiting the closing 110

movement of the valve to a partially open position and thereby maintaining a restricted communication between the interior of the valve and outlet passages —11— until the fluid pressure is sufficient to overcome the tension of its retracting spring.

To this end the tubular valve —12— is provided with a series of radial passages —15— normally extending in opposite directions from and beyond the stop shoulders —13— and —14— so that the effective size of the opening between the interior of the valve and passages —11— may be enlarged by the inward movement of the valve from its normal position.

This opening movement of the valve is produced automatically by the pressure of the fluid expelled by the impeller into the outlet —6—, said pressure being variable inversely as the "head" or height of the column of liquid from the terminal end —7— of the outlet.

For this purpose is provided a tubular piston —16— preferably formed integral with the tubular valve —12— coaxial with the inlet —5— of the case so that the valve and piston together constitute a tubular sleeve which is slidable endwise or axially within the opening —10— and an additional guide opening —17— in the case, the interior of said sleeve communicating with the inlet —5— of the case.

The piston —16— is formed by an enlarged central portion of the sleeve of which it forms a part and is located in the impeller chamber —18— between the outer end of the impeller and the adjacent side of the case where it is exposed to the pressure of the liquid from the outlet —6— through the impeller chamber.

A retracting spring —19— is located within the sleeve, as —20—, forming the valve —12— and the piston —16— and has one end bearing against the inner wall of the impeller and its other end engaged with an inturned annular shoulder —21— on the outer end of the sleeve for retracting said sleeve and thereby normally holding its shoulder —13— in engagement with the companion shoulder —14— or, in other words, normally maintaining the valve in a partly open position.

It is now evident that as the impeller and its supporting shaft —9— are rotated by any suitable means unnecessary to herein illustrate, the liquid will be drawn into the central inlet —5— and thence through the sleeve —20— from which it will pass through the openings —15— and passages —11— of the impeller and thence through the outlet passage (not shown) rising from the terminal end —7— of the outlet —6—.

Now, if the pump is operating under normal "head" and power for which it was designed, it will continue to deliver the re-

quired volume of liquid, but should the "head" be reduced for any reason tending to increase the volume of delivery, the decreased pressure of such liquid upon the piston —16— will allow the latter to be moved axially toward its normal position by the spring —19— for maintaining approximately the same volume of delivery as that for which the pump was designed under the maximum head.

It is to be understood that pumps of this character are designed to operate under an approximately predetermined head and volume of delivery, and that in many instances the pump is installed to operate under a considerably lower head than that for which it was designed, resulting in a corresponding reduction of back pressure and a proportionately increased volume of delivery unless some means is provided for preventing such increased volume of delivery.

The valve —12— and its retracting spring —19— are normally adjusted to allow the passage of water therethrough at the beginning of the operation of the pump and until the head reaches a predetermined (relatively low) level, whereupon as the head and consequent back pressure increases, the valve will be further gradually opened against the action of its retracting spring —19— and may continue to further open until the maximum head and volume of delivery for which the pump is designed is reached, at which time, the capacity of delivery will, of course, be practically constant.

In the event, for any reason, the pump should be used with a head considerably less than that for which it was designed, the back pressure will, of course, be correspondingly reduced and will allow a corresponding return of the valve —12— toward its normal position by the spring —19—, the tension of the spring tending to move the valve toward its normal position being so tensioned relatively to the maximum head pressure tending to open the valve against the action of the spring, that when the pump is used with a head materially below that for which it was intended, the gradual movement of the valve toward its normal position by the spring under the reduced pressure will automatically maintain approximately the same volume of delivery as when operated under the maximum head with the valve full open.

On the other hand, if the passage for the water to the impeller were to remain at its full capacity and the head were materially reduced, the volume of delivery would be correspondingly increased beyond the volume of delivery at the maximum head.

What I claim is:

1. In a centrifugal pump, an impeller case having an inlet and an outlet, an impeller having an inlet and passages communicat-

ing respectively with the first-named inlet and outlet, a valve controlling communication between the inlet and passages of the impeller and normally having restricted 5 communication with said passages, a piston actuated in one direction by pressure of the fluid discharged by the impeller and connected to the valve for gradually opening the latter as the liquid pressure increases 10 beyond a certain degree, and retracting means for the valve and piston.

2. In a centrifugal pump the combination of an impeller case having an inlet and an outlet, a rotary impeller in said case having 15 an inlet and passages communicating respectively with the inlet and outlet of the case, a valve movable across the inner ends of said passages, means actuated by pressure of the liquid discharged by the impeller for 20 gradually opening the valve as the pressure increases, and retracting means for said valve and piston.

3. In a centrifugal pump the combination of an impeller case having an inlet and an outlet, an impeller rotatable in said case and provided with an inlet and passages registering respectively with the inlet and outlet of the case, said inlets being coaxial with the axis of movement of the impeller, a tubular 25 valve coaxial with said inlets and movable axially across said passages, a piston ac-

tuated in one direction by pressure of the expelled fluid, and transmitting its motion to said valve for opening the latter as the pressure increases, and retracting means for 35 the valve and piston.

4. In a centrifugal pump the combination of an impeller case having an inlet and an outlet, an impeller rotatable in said case and provided with a central opening coaxial 40 with the inlet of the case and also having passages communicating with the outlet of said case, a valve movable in the central opening of the impeller across said passages and provided with an inlet communicating 45 with that of the case, coöoperative means between the impeller and valve for limiting the closing movement of said valve to a partly open position, a spring normally holding the valve in its partially closed position, and means actuated by pressure of the expelled fluid for gradually opening said valve against the action of said spring when the pressure is sufficient to overcome the tension of the spring. 50

In witness whereof I have hereunto set my hand this 10th day of November, 1919.

BENJAMIN J. KIME.
